UNITED STATES PATENT OFFICE

JOSEPH A. SEYMOUR, OF FABYANS, NEW HAMPSHIRE

BLADE HOLDER

Application filed February 18, 1929. Serial No. 341,006.

This invention relates to a blade holder, the general object of the invention being to provide means whereby blades of safety razors and the like can be placed in the holder so as to provide a cutting implement.

Another object of the invention is to so form the device that either double edged blades or single edged blades can be used with the device.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a perspective view of the device, showing a single edged blade therein.

Figure 2 is a section on line 2—2 of Figure 1.

Figure 3 is longitudinal sectional view showing a double edged blade used with the device.

Figure 4 is a sectional view showing a double edged blade used with the device.

Figure 5 is a view of the U-shaped member used with a double edged blade.

In these views, the numeral 1 indicates the handle of the device and 2 the blade holding part. The handle is of tubular construction, with portions of the metal flattened to provide the holding part 2. One edge of the holder part is rounded, as at 3, and a strip 4 of wood or the like is placed in this rounded part. The two parts 2' of the holder part 2 are spaced apart a sufficient distance to receive a blade 5 between them and these portions are formed with offset parts 2'' where they connect with the rounded part 3 to receive the thickened part 5' of a single edged blade, as shown in Figures 1 and 2. The blade is pushed into the holder part from the end thereof.

When a double edged blade, such as shown at 6 in Figure 4 is used, a substantially U-shaped strip 7 is placed over that edge of the

blade which is not being used, this strip taking the place of the thickened part 5' of the single edged blade and it fits in the space formed by the enlargements 2''. The ends of the member 7 are looped upon themselves, as shown at 7', so that they will overlap the portions 2'' and permit easy withdrawal of the blade and the member 7. The edge of the blade not being used will engage the wooden part 4 which acts to prevent dulling of the edge by coming in contact with a metal part. After one edge has become dull through use, the blade can be reversed and the new edge brought into use.

From the foregoing it will be seen that I have provided a simple form of holder in which the blades can be easily and quickly placed and removed and one in which the blades are firmly held.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A razor blade holder comprising a tubular handle part and a pair of flat extensions on the handle part, a tubular part connecting together adjacent side edges of the flat parts, said flat parts being provided with outwardly offset portions adjacent the tubular part for forming a wide space between the flat parts adjacent the tubular part and a narrow blade receiving space between those portions of the flat parts which are not offset, a strip of soft material in the tubular part and a U-shaped blade holding member removably fitting in the wide space and having its ends bent to form loops to engage the outer ends of the flat parts.

In testimony whereof I affix my signature.

JOSEPH A. SEYMOUR.
